UNITED STATES PATENT OFFICE.

MARCUS C. HOPKINS, OF WASHINGTON, DISTRICT OF COLUMBIA, ASSIGNOR TO HOPKINS CORPORATION, OF JERSEY CITY, NEW JERSEY, A CORPORATION OF DELAWARE.

DESIGN FOR A LOUD SPEAKER.

Application filed December 22, 1925. Serial No. 15,819. Term of patent 14 years.

To all whom it may concern:

Be it known that I, MARCUS C. HOPKINS, residing at Washington, in the District of Columbia, a citizen of the United States, have invented a new, original, and ornamental Design for Loud Speaker, of which the following is a specification, reference being had to the accompanying drawings, forming part thereof.

In the drawings, Fig. 1 is a front elevation, Fig. 2 is a rear elevation, Fig. 3 is an

end elevation and Fig. 4 is a plan view with a resonator panel tilted forward into a vertical position for better exposure of the related parts.

I claim:

The ornamental design for a loud speaker substantially as shown.

In testimony whereof I have signed the foregoing specification.

MARCUS C. HOPKINS.
